UNITED STATES PATENT OFFICE.

JOSEPH T. ROBIN, OF NEW YORK, N. Y.

APPAREL-BELT.

SPECIFICATION forming part of Letters Patent No. 653,688, dated July 17, 1900.

Application filed March 28, 1900. Serial No. 9,892. (No model.)

To all whom it may concern:

Be it known that I, JOSEPH T. ROBIN, a citizen of the United States of America, residing in the borough of Manhattan, city, county, and State of New York, have invented certain new and useful Improvements in Belts, of which the following is a specification.

My invention relates to belts, and more particularly to a frame employed in the making thereof.

I will describe a belt embodying my invention and then point out the novel features thereof in a claim.

In the accompanying drawings, Figure 1 is a view of a frame for use in making belts embodying my invention. Fig. 2 is a view similar to Fig. 1, but showing a modification. Fig. 3 is a sectional view taken on the line 3 3 of Fig. 1. Fig. 4 is a sectional view taken on the line 4 4 of Fig. 1. Fig. 5 is a view of a belt complete. Figs. 3 and 4 are drawn to a larger scale than Figs. 1 and 2.

Similar letters of reference designate corresponding parts in all of the figures.

A represents a frame the several parts of which are of elastic or spring material. Preferably spring-wire is employed. The frame comprises the longitudinal pieces a a, the end pieces a' a' for connecting together the longitudinal pieces a a, and a number of brace-pieces a² intermediate the end pieces. All of the pieces comprised in the frame are suitably connected together. In the present instance the several parts are connected by soldering. In Fig. 1 the longitudinal pieces are higher at their middle points, and consequently the middle brace-piece a² is longer than the others. In Fig. 2 the longitudinal pieces a a are straight. The longitudinal pieces may be bent to have any desired curve.

B represents muslin or other fabric inclosing the several parts of the frame. The ends of the muslin or other fabric inclosing the end and brace pieces of the frame are pasted to

the muslin or other fabric inclosing the longitudinal pieces a a, or, if desired, the coverings of the end and brace pieces may be put on first and the coverings of the longitudinal pieces afterward, they being pasted or otherwise secured to the coverings of the end and brace pieces. The purpose of the muslin or other fabric is to serve as a means for securing ribbon or other material with which the frame is to be covered in the formation of a belt. The arrangement of the fabric sections is such that they brace one another, and each section or part thereof is prevented from twisting around its portion of the frame. Another advantage in having the fabric coverings in strips is that the spaces between the parts of the frame are left open, thereby enabling the ribbon or other fancy covering to be easily attached. Instead of having the fabric in strips to leave the spaces above referred to the frame may be completely inclosed.

C represents the ribbon or other material covering the frame, which is shown in full lines in Fig. 5 and dotted lines in Figs. 3 and 4.

D represents rings secured in the loops provided in the ends of the material C.

E represents fastening-pieces for the ends of the belts.

What I claim as my invention is—

A resilient frame, for use in making belts, which is wider at its middle portion than at its ends, consisting of longitudinal pieces, straight end and brace pieces connecting the longitudinal pieces, and a covering for each brace and end piece and each longitudinal piece.

In testimony whereof I have signed my name to this specification in the presence of two subscribing witnesses.

JOSEPH T. ROBIN.
